WAISTBAND ASSEMBLY FOR GARMENT

Mandel D. Kuber, Rego Park, N.Y., and Burton B. Ruby, Michigan City, Ind., assignors, by mesne assignments, to Joseph Machine Co., Inc., New York, N.Y., a corporation of New York

Filed Dec. 11, 1958, Ser. No. 779,609
6 Claims. (Cl. 2-236)

This invention relates to garments, especially trousers, and more particular to a stiffened waistband for the same.

The primary object of the present invention is to generally improve garments, and more particularly the waistband region thereof.

One problem is a tendency of the top edge of the garment to turn downward at the waist. This is referred to as "roll over." The problem of roll over has been aggravated in recent years because of the growing use of thin fabrics. There has been an increasing use of tropical weight garments for summer wear; an increase in the use of synthetic materials which tend to be used in lighter weights than wool fabrics; and in general because of efficient heating of automobiles and rooms, the garments worn even in winter have become lighter. These light fabrics lack body and therefore have a greater tendency to roll over.

One object of the present invention is to provide a waistband construction which minimizes roll over even when dealing with lightweight fabrics.

To accomplish the foregoing general object, and other more specific objects which will hereinafter appear, the present invention resides in the waistband elements and their relation one to another as are hereinafter more particularly described in the following specification. The specification is accompanied by a drawing in which:

FIG. 1 shows a pair of trousers swung open at the front or fly;

FIG. 2 is a section showing a preliminary step in the manufacture of the waistband assembly, namely the stitching together of the canvas and the curtain;

FIG. 3 shows how these are stitched to the upper edge of the garment material;

FIG. 4 shows the addition of a stiffening tape made of a plastics material, to the upper edge of the canvas;

FIG. 5 shows the relation of the parts of the waistband assembly after the garment material has been turned down to normal position, and corresponds to a section taken approximately in the plane of the line 5-5 of FIG. 1;

FIG. 6 is a section similar to FIG. 5, but showing the use of a plastics material stiffening tape of much greater width;

FIG. 7 is a section through the back half of the garment, taken for example in the plane of the line 7-7 of FIG. 1; and

FIG. 8 is a front elevation of the complete garment drawn to reduced scale.

Referring to the drawing, and more particularly to FIG. 8, the garment here illustrated is a pair of trousers generally designated 12, and having the usual leg portions 14 and 16. The garment is openable at a fly 18, and is provided with belt loops to receive a belt at 20. In accordance with the present invention, the waistband assembly of the garment is provided with stiffening tapes at the top edge of the garment to prevent roll over, these tapes being indicated at 22 and 24. The garment is conventionally made up of four main sections which are stitched together at two outside seams 26 and two inside seams 28.

Referring now to FIG. 1, the rear quarters 30 and 32 are stitched together at 34. The front quarters are stitched together at 36. The front and rear quarters are stitched

2

together by the two side seams 26 previously referred to. The waistband assembly generally designated 40 usually comprises a stiff fabric material concealed by a lining material.

The stiff material is commonly called a "canvas" in the trade, although in practice it may be more in the nature of a buckram or cambric. The lining material within the canvas is commonly called a "curtain." The canvas and curtain may extend continuously around the entire waist portion of the garment, or may be in two halves, one extending from the fly to the rear seam 34, and the other extending in similar fashion around the other side of the garment, there then being a separation indicated at 42 in FIG. 1.

It is common to make this combination of canvas and curtain in a continuous length, a portion of which is stitched to a garment or a half garment, and then is severed at the proper point.

Referring now to FIG. 2 of the drawing, the canvas is indicated at 44. This is preferably bias cut, but sometimes garments such as trousers are made with a canvas which is not bias cut. The material is a relatively open weave of cotton or the like which is impregnated and stiffened.

The curtain material is indicated at 46. This may be cotton, silk, nylon or other desired material. In the case of trousers, the curtain material frequently is the same as the material used for the pockets. It too is preferably bias cut, although this is not essential. The curtain material is preliminarily stitched to the canvas near the lower edge of the canvas, as is indicated by the line of stitching 48. One common practice is to finish and seal the lower edge of the canvas with a tape of cotton material indicated at 49, and to reversely fold the edge of the curtain 46 in three thicknesses as indicated at 50, these parts all being secured by the line of stitching 48. This construction has the advantage of concealing subsequent blind stitching connecting the waist assembly to the pockets of the garment, as is described later.

Referring now to FIG. 3, the curtain 46 is next turned upward and is secured to the main garment material 52 by a line of stitching 54. This stitching preferably passes through the canvas 44, and the upper edge of curtain 46 is preferably folded downward or hemmed as indicated at 56.

The garment material 52 is next turned away from the upper edge of the canvas 44, as is indicated in FIG. 4 by the change from the broken line position 52' to the solid line position 52, thereby exposing the upper edge of the canvas so that it may be stitched to an extra stiffening tape 60. This is preferably done by means of a line of stitching 62 located near the top edge of the canvas, and the tape 60 is located with its upper edge at the top edge of the canvas. This stiffening tape 60 is preferably a plastics material, and one suitable material is polyethylene. In any case, a plastics material is selected which preferably is resistant to laundering, dry cleaning and the elevated temperature of ironing.

Referring now to FIG. 5, the garment material is turned downward, as indicated by the change from the broken line position 52' to the solid line position 52. The top edge of the garment is marked 64, and the stiffening tape 60 is at the top edge of the garment.

The curtain 46 usually begins somewhat below the top edge 64 of the garment, say one-half inch below, but this is not essential, particularly when using the stiffening tape 60 of the present invention. This is so because the original reason for displacing the curtain downward was to provide an area of garment material at 66, so that garment material will be exposed, rather than curtain material, when the top edge of the garment rolls over.

The stiffening tape 60 may vary greatly in width, and referring to FIG. 6, it will be seen that the trouser construction there shown is the same as in FIG. 5, except that the stiffening tape 70 is very much wider than the stiffening tape 60 in FIG. 5. We have employed stiffening tapes ranging in width from $\frac{5}{8}$ inch to $1\frac{1}{2}$ inches. When trousers are used with a belt located near the top of the trousers, the belt itself helps, and the stiffening tape may be narrow, say $\frac{5}{8}$ inch. When the style of the trousers is such that the belt is located well below the top of the garment, the stiffening tape is preferably made wider. Some trousers are made without belt loops and are constructed to be used without a belt, and in such case the stiffening tape is preferably quite wide, said $1\frac{1}{2}$ inches in width.

In FIGS. 5 and 7 attention is directed to stitching indicated at 72. This represents the blind stitching previously referred to as serving to connect the waistband assembly to trouser pockets or other parts of the garment. Such stitching is not essential, but is convenient in order to help keep the waistband assembly and pockets in position.

Reverting to FIG. 1 of the drawing, the stiffening tape is indicated at 60, and it will be seen that there are two lengths of stiffening tape, one in each of the front quarters of the garment. The stiffening tapes terminate short of the side seams, and no corresponding stiffening tape is provided in the rear quarters of the garment. This is the preferred form of the invention for several reasons. One is that roll over is a problem at the front of the garment, and the stiffening tape would be superfluous at the back. Another is that the shape of the human body is concave at the back, and does not as well adapt itself there to the presence of a stiffening tape, particularly in the larger widths. Still another is that the plastics material is somewhat expensive and it would be wasteful to use the material entirely around the garment when it is only needed at the front. Still another is that the use of two separate lengths at the front only, minimizes a problem of puckering caused by differential shrinkage as between the plastic tape and the fabric materials of the garment.

It is largely for the latter reason that the tape is not stitched to the canvas and curtain as a long continuous assembly, with the resulting three-part assembly then being stitched to individual garments. Instead, only the canvas and curtain are stitched to each other as a long continuous assembly. This assembly is stitched to the garment or garment halves while the garment is still open, so that the waist assembly and the garment material may be turned in opposite directions as shown in FIG. 3. It is only thereafter that the short pieces of plastic tape are stitched to the waist assembly, again while the garment is still open, as shown in FIG. 4.

The garment is completed by putting together the halves of the garment if they are separate; by completing the corners; by completing the flies at the front, and additional details such as stitching down the upper ends of the belt loops, etc.

Even before this, when the main garment material is turned down to its outside or final position, as shown in FIG. 5, the waist portion is pressed in a first steam pressing operation. This is called "underpressing" and may be done while the garment is still open. It is intended primarily to form and locate and fix the top edge 64 of the garment. In underpressing, the shape of the buck is different from that used in final pressing of the garment. After underpressing, some other operations take place such as blind stitching of the lower edge of the waist assembly to the pockets.

After completing the garment there is a second pressing operation in which the finished trousers are pressed, and at this time the trousers rest on a differently shaped buck. The problem of puckering arises because of differential

shrinkage, and because of the change in shape to which the plastic tape is forced in these operations.

Certain precautions in manufacture help eliminate the problem of pucker. One is the use of separate front pieces instead of a continuous band of plastic tape. We recommend a stitch length of ten stitches per inch. Shorter stitches seem to increase pucker. We recommend a low thread tension in the sewing machine.

A fine needle should be used, but this is in order not to unduly weaken the plastic tape at the stitch line 62 shown in FIG. 4. A No. 14 Singer or equivalent size needle may be used. The color of the tape is preferably beige or a neutral color which will not tend to show through even a light tropical-weight material.

15 The plastic used may be a vinyl compound, but we prefer linear (high density) polyethylene, because of its resistance to high temperature and other good qualities for the present purpose. New compounds now being developed may prove even better. The thickness of the tape has been exaggerated in the drawing for clarity. It is thin enough to be readily flexible around the waist of the wearer.

Reverting to FIG. 5, it will be seen that the garment waistband assembly comprises a band of stiff fabric material 44 acting as the canvas, and a curtain 46 stitched to the canvas near its lower edge, with the main garment material 52 being folded inwardly and downwardly over the canvas and being stitched at 54 to the top edge of the curtain. There is an additional stiffening tape 60 of plastics material located with its upper edge at the top edge of the canvas, and stitched to the canvas by means of a line of stitching 62. The stiffening tape preferably extends across the front half only of the garment, and in the case of trousers with a front fly, the stiffening tape consists of two pieces of material, one on each side of the fly, as is shown in FIGS. 1 and 8.

It is believed that the construction and method of assembly of the improved waistband, as well as the advantages thereof, will be apparent from the foregoing detailed description. It will also be apparent that while we have shown and described our invention in a preferred form, changes may be made without departing from the scope of the invention as sought to be defined in the following claims. In the claims the reference to "roll over" means rolling over of the top edge of the entire garment.

We claim:

1. A garment waistband assembly comprising a band of stiff fabric material acting as the usual stiffening fabric extending entirely around the waist of the garment, a curtain extending entirely around the waist of the garment and stitched to the stiffening fabric near the lower edge of the stiffening fabric and of said curtain, and additional stiffening tape made of a plastics material which does not fuse at ironing temperatures extending across the front half only of the waist of the garment and located with its upper edge at the top edge of the stiffening fabric and stitched to the stiffening fabric by means of a line of stitching located near the top edge of the stiffening fabric, the main garment material being folded inwardly and downwardly over the top edge of the stiffening fabric and tape and being stitched to the top edge of the curtain, the sole means for securing the tape to the garment being stitching, and said tape being sufficiently wide and stiff to discourage roll over.

2. A garment waistband assembly comprising a band of stiff fabric acting as the usual stiffening fabric extending entirely around the waist of the garment, a curtain extending entirely around the waist of the garment and stitched to the stiffening fabric near the lower edge of the stiffening fabric, and additional stiffening tape made of a linear polyethylene plastics material which does not fuse at ironing temperatures extending across the front half only of the waist of the garment and located with its upper edge at the top edge of the stiffening

fabric and stitched to the stiffening fabric by means of a line of stitching located near the top edge of the stiffening fabric, the main garment material being folded inwardly and downwardly over the top edge of the stiffening fabric and tape and being stitched to the top edge of the curtain material at a height well below the top edge of the garment, the sole means for securing the tape to the garment being stitching, and said tape being sufficiently wide and stiff to discourage roll over.

3. A garment waistband assembly comprising a band of bias-cut stiff fabric acting as the usual stiffening fabric extending entirely around the waist of the garment, a bias-cut curtain extending entirely around the waist of the garment and stitched to the stiffening fabric near the lower edge of the stiffening fabric and of the curtain fabric with a double reverse fold of curtain material adapted to later receive and conceal blind stitching to other parts of the garment, and additional stiffening tape made of a linear polyethylene plastics material which does not fuse at ironing temperatures extending across the front half only of the waist of the garment and located with its upper edge at the top edge of the stiffening fabric and stitched to the stiffening fabric alone by means of a separate line of stitching located near the top edge of the stiffening fabric, the main garment material being folded inwardly and downwardly over the top edge of the stiffening fabric and tape and being stitched to the top edge of the curtain at a height below the top edge of the garment, the sole means for securing the tape to the garment being stitching, said tape being concealed by the aforesaid curtain and garment material, and said tape being sufficiently wide and stiff to discourage roll over.

4. A fly-front trouser waistband assembly comprising a band of stiff fabric material acting as the usual stiffening fabric, a curtain stitched thereto, and two pieces of additional stiffening tape made of a plastics material which does not fuse at ironing temperatures each extending across the front quarter only of the waist of the trousers and each located with its upper edge at the top edge of the stiffening fabric and secured by stitching to the waistband materials, the main garment material being folded inwardly and downwardly over the top edge of the stiffening fabric and tape and being stitched to the curtain, the sole means for securing the pieces of tape to the garment being stitching, said pieces being disposed end to end on opposite sides of the fly and together extending across the front half only of the waist of the trousers, and said tape being sufficiently wide and stiff to discourage roll over.

5. A fly-front trouser waistband assembly comprising a band of bias-cut stiff fabric acting as the usual stiffening

fabric extending entirely around the waist of the trousers, a bias-cut curtain extending entirely around the waist of the trousers and stitched to the stiffening fabric near the lower edge of the stiffening fabric and of the curtain

- 5 fabric with a double reverse fold of curtain material adapted to later receive and conceal blind stitching to the pockets of the trousers, the two pieces of additional stiffening tape made of a linear polyethylene plastics material which does not fuse at ironing temperatures each extending across a front quarter only of the waist of the trousers and each located with its upper edge at the top edge of the stiffening fabric and stitched to the stiffening fabric above by means of a separate line of stitching located near the top edge of the stiffening fabric, the
- 10 main trouser material being folded inwardly and downwardly over the top edge of the stiffening fabric and tape and being stitched to the top edge of the curtain at a height below the top edge of the trousers, the sole means for securing the pieces of tape to the garment being stitching, said pieces being disposed end to end on opposite sides of the fly and together extending across the front half only of the waist of the trousers, said tape being concealed by the aforesaid curtain and garment material, and said tape being sufficiently
- 15 wide and stiff to discourage roll over.

- 20 6. A garment waistband assembly comprising a band of bias-cut stiff fabric acting as the usual stiffening fabric, a bias-cut curtain stitched thereto near the lower edge of said stiffening fabric and of the curtain fabric with a double reverse fold of curtain material adapted to later receive and conceal blind stitching to other parts of the garment, and an additional stiffening tape made of a linear polyethylene plastics material which does not fuse at ironing temperatures located with its upper edge at the top edge of the stiffening fabric and stitched to the stiffening fabric alone by means of a separate line of stitching located near the top edge of the stiffening fabric, the main garment material being folded inwardly and downwardly
- 25 over the top edge of the stiffening fabric and tape and being stitched to the top edge of the curtain at a height below the top edge of the garment, the sole means for securing the tape to the garment being stitching, said tape being concealed by the aforesaid curtain and garment material, and said tape being sufficiently wide and stiff to discourage roll over.
